CUFF FOLDING DEVICE

Joseph Lyska, Detroit, Mich.

Application November 14, 1934, Serial No. 752,928
Renewed October 18, 1937

9 Claims. (Cl. 223—37)

My invention relates to a new and useful improvement in a cuff folding device adapted for use in the manufacture of trousers and particularly in the formation of the cuff which is customarily formed at the end of the trouser leg.

It is an object of the present invention to provide a cuff folding device whereby the end of the trouser leg may be easily and quickly folded in position to form the cuff and retained in position for the pressing operation.

Another object of the invention is the provision of a device of this class whereby the end of the trouser leg may be folded into cuff forming position ready for the felling operation.

Another object of the invention is the provision of a device of this class which will be simple in structure, economical of manufacture, durable, compact, light, and easily and quickly operated.

Other objects will appear hereinafter.

The invention consists in the combination and arrangement of parts hereinafter described and claimed.

The invention will be best understood by a reference to the accompanying drawing which forms a part of this specification, and in which,

Figure 1 is a perspective view of one of the gripping members used in the invention.

Fig. 2 is a side elevational view of a gripping member showing it in its initial stage of operation.

Fig. 3 is a side elevational view of one of the gripping members showing it in its second position of operation.

Fig. 4 is a side elevational view of one of the gripping members in its final position of operation with a part broken away and a part shown in section.

Fig. 5 is a plan view of the device in position after the folding operation.

Fig. 6 is a sectional view taken on line 6—6 of Fig. 5.

As now customarily practiced in order to form a cuff on the end of the trouser leg it is necessary first that the trouser leg be first turned inside out and then cut to the proper length. There is then marked on the cloth at the proper distances from the end two lines to assist in determining the proper position of fold. The fabric is then folded upon itself until the bottom line is brought into registration with the upper line. At this stage of operation the goods are basted together at these lines and the loose fold is then felled. After this operation it is necessary to turn the trouser inside out to properly stretch them for pressing, and then the goods are pressed. After

the pressing operation the basting threads are removed and the trousers are again pressed to cover up the stitch marks left by the basting threads. The present invention eliminates all necessity for basting and will affect a considerable saving of labor. As shown in Fig. 5 I use a pair of stretchers, each of which is provided with an arm 9 so that the trouser leg 10 may be stretched into proper position for pressing. Each of the arms 9 is provided with a socket 11 in which may be engaged the flat faced prong 12 of a yoke formed from a piece of wire or other resilient material doubled upon itself. In normal position the arms 12 are spread apart a considerable distance greater than they would be when in operative position as shown in Fig. 5, so that when placed in position shown in Fig. 5 they exert an outward pressure on the arms 9 to tightly stretch the trouser leg and retain it in position for pressing.

Each of these stretchers comprises a preferably metallic body 13 which is formed flat and cut away as at 14 to provide the arm 9. Projecting upwardly from the body 13 is a piercing pin or prong 15 and mounted on the upper edge 16 of the body 13 is a strip 17 preferably formed from spring metal one end 18 of which is pressed upwardly from the surface 16 to provide a space for the reception of a piece of fabric. Swingably mounted on a lug or boss 19 is an arm 20 having an angularly turned furcation 21 at its pivoted end, and provided at its opposite end with the L shaped piercing prong 22. As shown in Fig. 2 the arm 20 is adapted to lie in engagement with the upper face of the arm 9. When in this position the end of the trouser leg may be engaged at its edge between the face 16 of the body 13 and the outwardly flexed end of the strip 18, at the same time the piercing prong 22 is inserted through the fabric so that the device lies outside of the trouser leg. The body 13 is then swung on the hook or piercing prong 22 as a pivot into the position shown in Fig. 3. In this position the prong 15 will project through the trouser leg and the portion 23 of the trouser leg will be doubled upon the main body 24. The arm 20 is then swung into the position shown in Fig. 4, thus again doubling the doubled-over portion upon the main body 24 of the trouser leg. It will of course be obvious that when the movement from Fig. 2 to Fig. 3 is made the device is swung inwardly of the trouser leg so that in the position shown in Fig. 3 the device is inserted in the trouser leg. As the arm 20 is swung over the projecting end of the prong 15 it will extend through

an opening 25 formed in the free end of the arm 20. This will form the cuff of the trouser and leave the edge portion 26 to be felled. It is believed obvious that when one of the devices is 5 inserted at the front crease of the trouser and another device at the rear crease of the trouser so that when the stretching handle is inserted in position as shown in Fig. 5 the trouser will be stretched tightly and ready for pressing. 10 When the trouser is pressed while the device is in the position shown in Fig. 5 the cuff will be pressed into its formed position and the tailor may then fell the edge portion 26 in the usual manner. 15 It is thus obvious that the formation on the cuff on a trouser leg becomes a very simple operation which may be easily and quickly performed. The formation of the part 12 flat faced prevents any undue rotation of the folding members so 20 that they are securely held in position properly aligned with each other when the stretching handle is inserted as shown in Fig. 5.

While I have illustrated and described the preferred forms of construction of my invention, I 25 do not wish to limit myself to the precise details of structure shown, but desire to avail myself of such variations and modifications as may come within the scope of the appended claims.

Having thus described my invention what I 30 claim as new and desire to secure by Letters Patent is:

1. A cuff forming device of the class described comprising an elongated flat body; a piercing prong projecting upwardly from one edge of said 35 body adjacent one end; a fabric engaging member for slipping over the edge of a trouser leg; a swingable arm mounted on said body and adapted for lying in alignment therewith when swung to either side of its pivot; and a piercing prong on said arm adjacent one end thereof, said prong being spaced from the point of 40 pivot of said arm a distance substantially equal to the width of the cuff to be formed.

2. A cuff forming device of the class described 45 comprising an elongated body; means on said body for engaging and holding the edge of a trouser leg; means on said body for engaging a trouser leg and forming a pivot point on which said body may be swung inwardly on the trouser 50 leg for folding the edge portion thereof upon itself; and means on said body for folding said folded portion upon itself to a width sufficient to form a cuff.

3. A cuff forming device of the class described 55 comprising an elongated body; means on said body for engaging and holding the edge of a trouser leg; means on said body for engaging a trouser leg and forming a pivot point on which said body may be swung inwardly on the trouser 60 leg for folding the edge portion thereof upon itself; means on said body for folding said folded portion upon itself to a width sufficient to form a cuff; and means on said body for engaging a trouser leg during the folding operation of said 65 folded-over portion.

4. A cuff forming device of the class described 70 comprising an elongated body; means on said body for engaging and holding the edge of a trouser leg; means on said body for engaging a trouser leg and forming a pivot point on which said body may be swung inwardly on the trouser 75 leg for folding the edge portion thereof upon itself; means on said body for folding said folded portion upon itself to a width sufficient to form a cuff; means on said body for engaging a trouser

leg during the folding operation of said folded-over portion; and spreading means for spreading said body outwardly to retain the trouser leg in position for pressing.

5. A cuff forming device of the class described, 5 comprising: an elongated body; means on said body for engaging a trouser leg and forming a pivot point on which said body may be swung inwardly of the trouser leg and folding the edge portion thereof upon itself; and means on said body for folding said folded portion upon itself to a width sufficient to form a cuff.

6. A device for folding a cuff on a trouser leg or the like in the form of a flat folded fabric tube having diametrically opposed edge creases, 15 which comprises a pair of tools, one for each crease, each tool having two relatively movable portions, the first of which is movable with the second to stuff the end of the trouser leg inwardly upon itself and the second of which is 20 thereafter movable with respect to the first to roll or fold outwardly the fold thus formed to fold an outside cuff, each tool being provided with means to retain its portions stationary and to retain the trouser leg portions in the position 25 they assume after each manipulation of the tool, each tool portion having means for grasping the trouser leg at a crease, which means are spaced apart a distance predetermined to be the distance between the upper edge of the folded cuff and the edge to be felled, measuring around the folded cuff.

7. A device for folding a cuff on a trouser leg or the like in the form of a flat folded fabric tube having diametrically opposed edge creases, 35 which comprises a pair of tools, one for each crease, each tool having two relatively movable portions, the first of which is movable with the second to stuff the end of the trouser leg inwardly upon itself and the second of which is 40 thereafter movable with respect to the first to roll or fold outwardly the fold thus formed to fold an outside cuff, each tool being provided with means to retain its portions stationary and to retain the trouser leg portions in the position 45 they assume after each manipulation of the tool, each tool portion having means for grasping the trouser leg at a crease, which means are spaced apart a distance predetermined to be the distance between the upper edge of the folded cuff and the edge to be felled, measuring around the folded cuff, the tool portions being movably connected at a point between these grasping means 50 spaced from one of them a distance equal to the length of the cuff, whereby the trouser leg 55 may be folded outwardly to form an outside cuff after an end edge of the trouser leg is stuffed inwardly into the trouser leg.

8. A tool for forming a conventional cuff on the end of a trouser leg or the like comprising a flat blade near one edge of which, between the blade ends, is pivotally mounted an arm, means at the free end of the arm for grasping the crease of the trouser leg and spaced from the arm pivot a distance equal to the desired length 60 of the cuff, and means on the blade for grasping the crease of the trouser leg and spaced from the arm pivot a distance no less than the desired length of the inwardly stuffed part of the trouser leg end, the arm pivot being between the two 65 means aforesaid.

9. A tool for forming a conventional cuff on the end of a trouser leg or the like comprising a flat blade near one edge of which, between the blade ends, is pivotally mounted an arm, 70

means at the free end of the arm for grasping the crease of the trouser leg and spaced from the arm pivot a distance equal to the desired length of the cuff, and means on the blade for grasping the crease of the trouser leg and spaced from the arm pivot a distance no less than the desired length of the inwardly stuffed part of the trouser leg end, the arm pivot being between

the two means aforesaid, the blade and arm being movable as a unit around the crease grasping part of the arm to stuff a fold of the trouser leg inwardly into the latter, after which the arm may move around its pivot to fold a cuff outwardly. 5

JOSEPH LYSKA.
